COMPENSATING MEANS FOR SOLE SEWING
MACHINES

Victor Petrosino, Wheeling, W. Va.

Application April 16, 1945, Serial No. 588,509

8 Claims. (Cl. 112—48)

(Granted under the act of March 3, 1883, as
amended April 30, 1928; 370 O. G. 757)

1

The invention described herein, if patented may be manufactured and used by or for the Government for governmental purposes, without the payment to me of any royalty thereon.

My invention relates to improvements in sewing machines for stitching the outsoles of shoes and is concerned with a new and improved means for compensating for the abnormal play due to wear between the moving elements concerned directly in feeding work through the machine, and more particularly, it relates to means for eliminating the horizontal and vertical play due to wear between the feed adjusting lever slide block and the arcuate slideway in the feed cam lever and between the feed slide and feed slide guide of the machine.

Machines for stitching outsoles to the welts of shoes are being extensively used by the trade, a common type of machine including an awl mounted on a shaft and adapted to be angularly oscillated upon the shaft for piercing the work and also to be moved horizontally forwardly and backwardly along the shaft for feeding the work through the machine. Horizontal movement is imparted to the awl by a feed slide which in turn is driven by a feed cam lever pivotally mounted to a fixed part of the machine and operatively connected to a cam on the machine which causes the feed lever to oscillate when the machine is operating. It will be obvious that these parts are subject to considerable wear in the normal operation of a machine because they make one complete oscillation for each stitch taken, yet the awl must operate between close limits and be properly coordinated with the needle otherwise a poor grade of work is turned out by the machine, and it is subject to mechanical difficulties such as breakage of needles, needle guides and awls. Replacement of the operating parts of the feeding mechanism each time they become worn would be impractical because of the expense involved, and as a result attempts have heretofore been made to devise some means for compensating for excessive play due to wear between the feed slide and feed slide guide and between the feed cam lever and its associated moving parts, but none of these attempts have been successful because they did not eliminate both horizontal and vertical play. My improved compensating means is constructed so that play in both directions may be compensated for by separate means each adjustable independently of the other.

It is accordingly an object of the invention to provide a new and improved means for compensating for play and looseness in the feeding

2

mechanism of a sole stitching machine which means is adjustable to provide compensation progressively for the wear resulting from ordinary use of the machine and which eliminates the need for replacement of the feed slide, feed slide guide, feed cam lever and feed adjusting slide block when these parts become worn.

Another object of the invention is the provision of a new and improved means for compensating for wear in the feeding mechanism of a sole stitching machine by which proper coordination between the parts of the feeding mechanism may be maintained at all times so that breakage of needles, needle guides and awls is greatly reduced, better operation of the machine is obtained and as a result a neater and better grade of work can be turned out on the machine.

A further object of the invention is the provision of a new and improved means for compensating for wear in the work feeding mechanism of a sole stitching machine which is so constructed that it may be installed and used on any of the many different makes and models of sole stitching machines now in common use without extensive alteration of such machines, and which may be installed on either new machines or machines that have already seen much service.

A still further object of the invention is the provision of a new and improved means for compensating for wear in a sole stitching machine which is inexpensive to manufacture, yet durable and wholly effective for compensating for wear in the machine, is readily installed on such machine, and is easily and quickly adjustable to provide the desired compensation.

These and other objects of the invention will become apparent from the following description and accompanying drawings in which:

Figure 1 is a fragmentary view of a sole stitching machine showing only the work feeding mechanism and associated parts.

Figures 2 and 3 are a top plan view and a front elevational view, respectively, of my new and improved retaining bar for holding the feed slide of a sole stitching machine in position.

Figure 4 is a sectional view taken on the line 4—4 of Figure 2.

Figure 5 is a top plan view of a gib or wear plate for use with the retaining bar.

Figure 6 is a sectional view taken on the line 6—6 of Figure 2.

Figure 7 is a fragmentary top plan view of a feed cam lever for a sole stitching machine.

Figure 8 is a fragmentary side elevational view 55 of the feed cam lever.

Figure 9 is a bottom plan view partly in section of the arcuate slideway in a feed cam lever.

Figure 10 is a perspective view of the gib used in the slideway of a feed cam lever.

Referring to the drawings, my invention is shown as applied to a curved needle sole stitching machine in which the work is fed through the machine by the awl. This type of machine is of known construction and in wide use so that a detailed description of its structure is not thought to be necessary, and this description will be limited to those parts of the machine with which my improved structure is directly connected.

The various working parts of a machine are supported on the main supporting column 12 by a complicated structure unnecessary to describe, but including a head in which a main drive shaft is rotatably mounted and a forwardly extending shelf or table 13 provided with ways 14 forming a guide 15 in which a feed slide is adapted to reciprocate horizontally. In a sole stitching machine of this type the work is held in position on a work table by a presserfoot and is fed by an awl, the operator merely guiding the edge of the shoe as the sole is drawn by the awl over the work table between it and the presserfoot. A shoe edge guard and an edge gauge which engage the shoe are provided for aiding the operator in properly guiding the shoe as it is advanced through the machine. All of these parts are of conventional construction and have not been described or illustrated in detail as they form no part of the invention.

A feed slide 16 is provided which consists of a rectangular plate adapted to slide in the guide 15 provided with a rabbeted forward longitudinal edge and an integral vertically extending arm 17 at one end of the plate as seen in Figure 1. The awl which not only perforates the work for the needle but also feeds it forward during the perforating stroke is secured by an awl clamp to an awl holder segment both of known construction which are suitably mounted for angular and linear oscillation upon a horizontally extending stud located adjacent the upper end of the arm 17.

Slide 16 is retained in position for horizontal reciprocatory movement by a flat rectangular retaining bar indicated at 18 in Figures 1 to 6 and provided with a plurality of vertical apertures 19 adjacent its front edge for the reception of stud bolts 20 which extend through these apertures and are threaded into the top of the table 13 for securing the bar on the table top.

The detailed construction of my improved retaining bar 18 is shown in Figures 2 to 6, inclusive from which it will be apparent that the bar is of elongated rectangular shape and is provided with an elongated cut-out portion 21 along one of its edges. This cut-out portion 21 preferably extends inwardly from the lower back edge of the bar for approximately one third its width and has a depth approximately one third the thickness of the bar. A plurality of vertically extending tapped apertures 22 are provided in the bar along the longitudinal center line of this cut-out portion 21 for the reception of adjusting screws 23. A second series of apertures 24 extending transversely of the bar from its front side and intersecting the vertical apertures 22 are provided which are tapped from their outer ends for a portion only of their length as indicated in Figures 2 and 6 and receive locking screws 25 for locking the adjusting screws 23. To complete the structure of the retaining bar it is provided with an elongated wear plate or gib 26 adapted to fit

snugly in the cut-out portion of the bar and provided with countersinkings 27 spaced in aligned relation with the vertical apertures 22 in the bar 18 when the gib is in position in the cut-out portion 21. When the bar 18 is secured in position on the table 13 by means of the stud bolts 20 its back edge projects over the slideway 15 a distance equal to the width of the gib 26 and this projecting portion engages an edge of the feed slide 16 thereby serving to retain the slide in the slideway and guide it as it is reciprocated horizontally so that the head of the arm 17 will move the awl sector backward and forward on the awl shaft and thus move the work in a feeding direction.

In the operation of a machine of this type the feed slide 16 and retaining bar 18 are subject to considerable wear which if not in some way compensated for results in a relatively large amount of vertical play between the moving parts that interferes with the proper coordination and operation of the machine causing increased breakage of awls, needles and needle guides. To be effective the compensating means must be adjustable so that it can be progressively adjusted at intervals as the wear on the parts increases. In my improved mechanism such adjustment is secured through the adjusting screws 23 which have tapered ends 28 that engage in the countersinkings 27 in the gib 26 and assist in retaining the gib in position. The adjusting screws are locked in position by means of the locking screws 25 threaded into the tapped ends of the transverse apertures 24 and bearing at their inner ends against brass plugs 30 which are thereby forced against the sides of the adjusting screws 23 and lock them in position. In making an adjustment of the gib 26 to compensate for wear the locking screws 25 are first loosened and the adjusting screws 23 then turned down as far as they will go. They are then backed off approximately half a turn and the locking screws 25 again tightened. This adjustment will provide sufficient play between parts to permit unimpeded reciprocation but will not result in the excessive looseness or play between the parts.

The mechanism for driving the feed slide will now be described. Referring to Figure 1 a feed cam lever is indicated at 32 adapted to fulcrum on a vertically extending fulcrum pin 33 which extends through the lever and is suitably secured as by a set screw 34 in one end of a feed cam lever bracket 35 which has its opposite end secured to a fixed part of the head of the machine by any suitable means. A rearwardly extending arm 36 on the feed cam lever 32 has a cam follower roll 37 on its outer extremity which engages in a cam groove 38 in a cam 39 mounted on the main drive shaft of the machine so that upon rotation of the drive shaft the feed cam lever 32 is oscillated with a predetermined frequency. Extending forwardly from the feed cam lever 32 is an arcuate channeled arm 40 which forms an inverted arcuate shaped slideway 41 as best seen in Figure 9 in which an apertured feed adjusting lever slide block 42 is adapted to slide. This block forms a part of the operating connection about to be described between the feed cam lever 32 and the feed slide 16 by means of which angular oscillation of the former is translated to linear reciprocation of the feed slide for moving the awl in a work feeding direction.

Suitably mounted as by means of a stud 43 on the feed slide 16 adjacent the arm 17 is a feed adjusting lever bracket 44 which is adjustable

5

by means of an adjusting screw 45. This bracket has a laterally extending arm upon which one end of a feed adjusting lever 46 is pivotally secured. Intermediate the ends of the lever a stud is secured therein which is adapted to be pivotally received in an aperture 47 in the sliding block 42, as best seen in Figure 9. Thus the portion of the lever 46 between this stud and its secured end along with the slide block 42 forms an operating connection between the feed slide 16 and the feed cam lever 32. The free end of the lever 46 extends outwardly beyond the arcuate slideway 41 and has a portion 48 adapted to be gripped by the hand of an operator and a ratchet pawl 49 for engaging the teeth of a feed adjusting ratchet 50 secured to the slide 16. By moving the lever 46 along the ratchet 50 the relative position of the slide block 42 in the slideway 41 is altered and in this manner the length of the stitch taken by the machine may be varied. When a long stitch is desired, the adjusting lever 46 is moved to bring the slide block 42 close to the forward or outer end of the slideway 41 and when a shorter stitch is desired it is moved in the opposite direction.

Since one complete oscillation of these parts occurs for each stitch taken, it is obvious that the sides of the arcuate slideway 41 and the slide block 42 are subject to considerable wear during operation of the machine which permits excessive horizontal play if no compensation is provided therefor. In Figures 7 to 10 inclusive, I have shown means for compensating for this wear which may be progressively adjusted to compensate for increased wear as it occurs.

Referring to these figures, it will be seen that the adjusting means includes a brass gib 51 of approximately the same height as the depth of the slideway 41 which gib is mounted on the inner face of the outer wall 52 of the two arcuate walls forming the slideway 41 and extends from end to end of wall 52. This gib 51 has its ends turned back to form resilient hooks as shown at 53, and these hooks snap over the ends of the wall 52 to hold the gib 51 in position. The outer wall 52 is provided with tapped apertures 54, three being shown in the drawings, for the reception of adjusting screws 55 which are threaded into these apertures and are locked in any desired position by means of lock nuts 56. When excessive play develops between the slide block 42 and the sides of the arcuate slideway 41, the lock nuts 56 are loosened and the adjusting screws 55 turned sufficiently to move the gib 51 out far enough to compensate for this play. The lock nuts 56 are then tightened thereby locking the adjusting screws 55 in position. In this way, very small and very accurate adjustments may be made between these moving parts to prevent excessive horizontal play therebetween.

In feeding work through the machine, the awl makes one complete reciprocatory movement for each stitch taken and during the piercing stroke moves the work forward for the stitch, this feeding movement being imparted to it by the horizontal reciprocation of the feed slide 16 which, in turn, is operated by the oscillating feed cam lever 32 through the feed adjusting lever 46 and slide block 42. It will be apparent that considerable play will soon develop between these moving parts when the machine is in use. Such play, even though slight, is detrimental to the proper operation of the machine because of the close limits between which the awl and needle and needle guide must be adjusted to operate

6

properly, and the accurate adjustment necessary cannot be secured or maintained if more than the very limited predetermined amount of play is present in the parts which operate the awl. Formerly, this could be remedied only by replacements of some or all of the moving parts such as the feed slide, feed slide guide, slide block or feed cam lever, depending on which of these parts were worn, but this is no longer necessary. My invention not only saves the cost of replacement of these parts and much of the amount formerly spent on needles, needle guides and awls, but it also saves much time because the adjustment can be made very quickly, and it is not necessary to tear down the machine to do so. Furthermore, my invention is equally adaptable to use on new machines or on machines that have already seen much service.

A specific form of compensating means has been illustrated and described herein for the purpose of illustrating the invention but it will be obvious that modifications in the form, size, and arrangement of parts may be made without departing from the scope of the invention which is to be interpreted to include all those modifications coming within the scope of the appended claims.

I claim:

1. In an awl feed sole stitching machine having a work feeding awl horizontally reciprocable by a reciprocating feed slide for moving the awl in a work feeding direction and a feed cam lever fulcrumed on said machine for imparting reciprocatory movement to the feed slide when the cam lever is oscillated by the machine, the combination comprising a raceway for guiding the reciprocatory movement of said feed slide, a slideway on said feed cam lever, a working connection operating in part in said slideway for translating the oscillatory movement of said cam lever to reciprocatory movement in said feed slide, gibs positioned along said raceway and said slideway to form a bearing surface between the same and said reciprocating and oscillating parts for sustaining the wear therebetween, resilient means for maintaining the gib in the slideway, and means for adjusting said gibs to progressively compensate for wear between said parts.

2. In an awl feed sole stitching machine having a work feeding awl horizontally reciprocable by a reciprocating feed slide for moving the awl in a work feeding direction and a feed cam lever fulcrumed on said machine for imparting reciprocatory movement to the feed slide when the cam lever is oscillated by the machine, the combination comprising a feed slide guide for guiding the reciprocatory movement of said feed slide, a bar for retaining said feed slide in said guide for reciprocatory movement therein, said bar provided with an elongated cut-out portion, a gib mounted in the cut-out portion and forming the bearing surface between said feed slide and said retaining bar, a slideway on said feed cam lever, a connection operating in part in said slideway for reciprocating said feed slide when said cam lever is oscillated, a gib positioned along one face of said slideway to form a bearing surface therein, means for individually and progressively adjusting said gibs to compensate for wear between the moving parts and prevent excessive vertical play between said feed slide and said retaining bar and excessive horizontal play between said slideway and connection, and means for locking said adjusting means.

3. In an awl feed sole stitching machine hav-

ing a feeding mechanism including a feed slide horizontally reciprocable for moving work in a feeding direction, the combination comprising an elongated bar for slidably engaging said feed slide to hold the latter in position, said bar provided with an elongated cut-out portion, a gib interposed between said bar and said feed slide and mounted in said cut-out portion, means for adjusting the vertical position of the gib to compensate for wear between said feed slide and said gib and means for locking said adjusting means.

4. In an awl feed sole stitching machine having a work feeding mechanism including a feed slide horizontally reciprocable in a feed slide guide for moving work in a feeding direction, the combination comprising a retaining bar having an elongated cut-out portion in one of the longitudinal edges thereof, a gib in said cut-out portion to form the bearing surface between said bar and said slide, spaced seats in said gib, means for securing said retaining bar over said slide guide to hold said feed slide in position for reciprocation in said slide guide, means for adjusting the vertical position of said gib to compensate for wear between said feed slide and said gib, said adjusting means engaging in said seats for assisting in securing said gib in position, and means for locking said adjusting means.

5. In an awl feed sole stitching machine having a work feeding mechanism including a feed slide horizontally reciprocable in a feed slide guide for moving work in a feeding direction, the combination comprising an elongated bar secured to said slide guide for retaining said feed slide in said guide in reciprocable relation therewith, said bar having an elongated cut-out portion in one of the longitudinal edges thereof and a plurality of tapped vertical apertures in said cut-out portion of said bar intersected by apertures extending transversely from the front side of said bar, said transverse apertures being tapped for a portion of their length from their outer ends, a gib adapted to be received in said cut-out portion and projecting therefrom to form the bearing surface between said bar and said slide, a plurality of seats in said gib aligned with the vertically extending apertures in said bar, adjusting studs threaded in the vertical apertures of said bar for adjusting the vertical spacing between said bar and said gib, said studs engaging in said seats for assisting in securing said gib in position, loose plugs in the inner ends of said transversely extending apertures and locking screws receivable in the threaded ends of said transversely extending apertures, said screws bearing against said plugs to force said plugs against said adjusting screws for locking the latter.

6. In an awl feed sole stitching machine having horizontally reciprocable means for moving work in a feeding direction and a feed cam lever

fulcrumed on said machine and oscillated by a driving cam on said machine for reciprocating said work feeding means, the combination comprising a slideway on said lever, a working connection secured on said feeding means having a part slidable in said slideway, a gib adapted to be secured in said slideway for sustaining the wear between said slideway and said connection, resilient means for securing said gib in position in said slideway, and means for adjusting said gib to compensate for wear and prevent excessive horizontal play between said slideway and connection.

7. In an awl feed sole stitching machine having horizontally reciprocable means for moving work in a feeding direction and a feed cam lever fulcrumed on said machine and oscillated by a driving cam on said machine for reciprocating said work feeding means, the combination comprising a slideway on said lever, a working connection on said feeding means having a part slidable in said slideway, a gib adapted to be secured in said slideway for sustaining the wear between said slideway and said connection, resilient means for securing said gib in said slideway, adjusting screws for adjusting said gib to compensate for wear between said moving parts and prevent excessive horizontal play between said slideway and connection and lock nuts for locking said adjusting screws.

8. In an awl feed sole stitching machine having horizontally reciprocable means for moving work in a feeding direction and a feed cam lever fulcrumed on said machine and oscillated by a driving cam on said machine for reciprocating said work feeding means, the combination comprising an arcuate slideway on said lever, a working connection on said feeding means having a part slidable in said slideway, an arcuate gib adapted to be secured in said slideway for sustaining the wear between said slideway and said connection, resilient means for securing said gib in said slideway, adjusting screws in one of the walls of said slideway for adjusting said gib to compensate for wear between said moving parts and prevent excessive horizontal play between said slideway and connection and lock nuts for locking said adjusting screws.
